Dear N. Reinthal

UNITED STATES PATENT OFFICE.

WOLFGANG E. SCHWARZMANN, OF LONGMEADOW, MASSACHUSETTS, ASSIGNOR TO
AMERICAN BOSCH MAGNETO CORPORATION, OF NEW YORK, N. Y., A CORPORATION
OF NEW YORK.

TIMING MECHANISM.

1,418,175.

Specification of Letters Patent. Patented May 30, 1922.

Application filed December 11, 1920. Serial No. 430,015.

To all whom it may concern:

Be it known that I, WOLFGANG E. SCHWARZMANN, a citizen of the United States, residing at Longmeadow, in the county of Hampden, State of Massachusetts, have invented certain new and useful Improvements in Timing Mechanism; and I do hereby declare the following to be a full, clear, and exact description of the invention, such as will enable others skilled in the art to which it appertains to make and use the same.

The present invention relates to adjustable timing devices for magnetos, and particularly one adapted to be carried by the interrupter housing of the magneto.

An ignition system almost invariably provides variable timing periods to suit different speed and load conditions imposed upon the engine with which it is associated. To that end, the mechanical interrupter of the magneto or sparking coil has an adjustable member to which is attached a timing member connected by an adjusting rod or wire 25 to the control lever on the steering wheel or post of an automotive vehicle or a convenient part of a stationary organization. Heretofore, it has been customary to fasten a timing arm to the adjustable member of the interrupter by a screw or other securing means for rigidly connecting them together, but in such arrangement the adjusting pull on the control lever is applied at a single point of the periphery of the adjustable member and 30 sometimes causes the adjustable member to bind in its bearing, particularly if a decided increase in the resistance develops in the bearing.

It is often necessary for the timing member to be located on one side or the other of the adjustable member of the interrupter, or above or below it, or at some intermediate point, in order that the control lever may be attached to it most conveniently. The adjustable member is ordinarily in the form of a ring carrying cams which are periodically engaged by the deflectable element of a pair of contact carrying elements. These cams are accurately positioned and fastened in 45 the adjustable member, or cam ring, by the manufacturer of the interrupter, and therefore, the engine builder is frequently inconvenienced in installing the magneto or the adjusting rod or wire. To meet this difficulty, the adjustable member or cam ring of the interrupter has been provided with

slots into a selected one of which is set a lug carried by the timing ring surrounding the cam ring, and to the timing ring is attached a timing arm connected to the rod 60 or wire, as above stated. While this arrangement provides for several positions of connection, it does not, however, provide for universal relative angular adjustability of the timing ring and cam ring, and it also 65 requires a thicker adjustable member to provide for the slots. This results, as before, in a single point of application of the adjusting pull to the adjustable member. Furthermore, the timing ring is not positively 70 prevented from working off from the adjustable member in an axial direction as a result of the continual vibration to which it is subjected by the engine.

The timing ring is usually rigid or integral with the timing arm, both having a common radial slit to permit a certain amount of flexing of the ring halves and the arm portions on each side of the slit in the arm. A clamping screw is used to flex the 80 parts so as to clamp the ring halves upon the periphery of the cam ring. The pressure thus applied by the timing ring upon the cam ring forces the latter out of the true circular shape and a uniform result can 85 never be produced due to the eccentricity of the rings upon the contraction of the split timing ring. Furthermore, such timing ring can grip the cam ring at only two points, or but a few points, around its 90 circumference instead of substantially the whole circumference or periphery thereof. Such structure cannot meet the requirements of providing a connection adapted for all desired angular relations between the timing arm and the adjustable interrupter element nor the precise cooperation necessarily required in a magneto between the stationary and rotatable elements of the interrupter.

With the above in view and with the object of producing a simpler, cheaper and more efficient device, I have in accordance with one part of my invention, devised an adjustable timing device comprising an annular band parted or split along a radius thereof and having radially extending portions at said parting between which is placed an end of a timing arm and to which such end of the arm is attached by suitable securing means, the latter acting to tighten the band about the cam ring on the inter-

rupter housing in any relative angular position, the forces, acting to cause the band to tighten, being equally applied to the radially extending portions substantially 5 along a plane tangential to the periphery of the cam ring at the point or line of parting so that the binding stress will be imposed upon the band along its circumference with a resultant uniform distribution 10 of pressure along the contacting surfaces of the band and cam ring, and with a tendency to shorten the circumferential length of the band so as to cause the inner end of the timing arm to be forced radially inwardly 15 against the periphery of the cam ring to more effectively, positively maintain the timing arm and cam ring in adjusted relation.

In accordance with another part of the 20 invention the radially extending portions of the band have reinforcing return-bent portions which give increased thickness and rigidity to the radially extending portions.

As another part of the invention, whether 25 or not the radially extending portions have, although preferably having, reinforcing portions, the timing arm has one or more tongues located between the radially extending portions of the band and secured to such 30 portions by suitable securing means, the latter serving as a common means for drawing the radially extending portions toward each other for a uniform tightening of the band about the cam ring, as well as for securing such portions to the end, tongue or 35 tongues of the timing arm and for radially drawing the inner end of the tongue or tongues into firmer engagement with the outer surface of the cam ring.

As another part of the invention, whether 40 or not the radially extending portions have, although preferably having, reinforcing portions, the timing arm is slotted to provide flexible tongues to which the radially extending 45 portions of the band are secured so that as the tongues are flexed by the securing means the radially ending portions of the band are caused to mutually approach under 50 balanced stresses acting in planes substantially tangential to the periphery of the cam ring so as to produce a uniform tightening of the band about the cam ring and an inward draw in a radial direction of the inner end of the tongue against the periphery of 55 the cam ring.

In the accompanying drawing illustrating 60 preferred and modified embodiments of the invention:

Fig. 1 is an end view in elevation of one 65 form of device, constructed in accordance with my invention, in connection with a cam ring of a mechanical interrupter; Fig. 2 is a side view of the same; Fig. 3 is a top plan view of the same; Fig. 4 is a transverse section of the same; Fig. 5 is a

side view of the band; Fig. 6 is a view of a modified form of the band and timing arm in end elevation; Fig. 7 is a top plan view thereof; and Fig. 8 is a sectional view.

Referring more particularly to the drawing, the adjustable timing device illustrated in Figs. 1 to 5 inclusive, comprises a timing arm 1 having an aperture 2, in which may be connected the timing rod or wire leading to the steering wheel or other convenient accessible part of the vehicle, and having an end portion 3 preferably in the form of a tongue. The binding or clamping ring 4 is of annular form and is cut, split or parted along a radius thereof so that the band may expand or contract. The band preferably has integral radially extending portions 5, at the point of parting, between which is located the tongue 3 of the timing arm, a securing means, such as a screw bolt 6, passing through suitable apertures provided in both of the radially extending portions 5, and the tongue 3 for rigidly securing said portions and tongue together, as is clearly shown in Fig. 1. Each radially extending portion is preferably provided with a return-bent portion 7 folded back upon the portions 5 so as to form therewith a thickened and more rigid extension.

It will be apparent that the tongue is relatively thin so that the portions 5 may be located as practically near to each other as possible whereby as the binding screw or bolt causes the members 5 to mutual approach, the forces acting upon the band 4 to contact its size will act substantially in a plane tangential to the periphery of the cam ring 8 at the point or line of parting of the band 4. It will further be noted that the securing bolt or screw serves both purposes of tightening the band upon the cam ring, by causing a relative approach of the portions 5, and securing the latter rigidly to the tongue 3 of the timing arm. It will be further noted that the band 4 is relatively thin so as to have substantial flexibility for the purpose herein-after more fully shown.

Referring to the embodiment illustrated in Figs. 6, 7 and 8, the adjusting device comprises a timing arm 9 having an aperture 10, for the reception of an end of a timing rod 11 or wire leading to a convenient accessible part of the vehicle, and a slit 11 cut into one end of the arm so as to provide tongues 12 on each side of the slit, the tongues being capable of flexing under suitable stress. The relatively thin and flexible band 13 preferably has integral radially extending portions 14 disposed in spaced parallel relation and secured upon the outer surfaces of the tongues 12 by a suitable securing means, such as a binding screw or bolt 15 passing through and operative in suitable apertures provided in the portions 14 and tongues 12.

As the securing screw is operated the tongues 12 are flexed to mutually approach.

The radially extending portions 14 also approach each other accordingly and the band 13 is contracted so as to firmly bind or tighten upon the cam ring 8.

5 It will be noted that in both forms of device shown the application of forces or stresses is divided equally between the radially extending portions since the stresses are applied simultaneously and in opposite directions so that the binding or tightening effect of the band will be equally or uniformly distributed throughout the surfaces of contact between the band and the cam ring. The forces or stresses are applied close 10 to the periphery of the cam ring so that as the ends of the band are drawn together these forces will act substantially along a plane tangential to the cam ring at the point or line of separation between the ends of 15 radially extending portions of the band, so that the resultant forces acting through the band will be substantially along the circumference of the band. As the band is contracted there is a tendency to shorten its circumferential length and hence is circular size whereupon the inner ends of the tongue 20 3 or tongues 12 are drawn inwardly radially against the surface of the cam ring for firm engagement therewith, such engagement becoming greater upon the greater tendency 25 to contract the band. In use, the band in expanded condition is placed over the cam ring and the tongue or tongues of the timing arm inserted between the radially extending portions 30 of the band after which the securing means or screw is inserted in place. Just before tightening the securing means the timing arm and the band is rotated to any desired angular position with respect to the 35 cam ring before contracting the band upon the cam ring, thus providing a universal adjustment of the device relative to the cam ring, and hence, the interrupter elements. The screw is then tightened to contract the 40 band about the cam ring and to cause the radially extending portions to bind with the tongue or tongues of the timing arm and to firmly engage the periphery of the cam ring, the securing means serving as a common 45 means for both functions of contracting the band and of securing the timing arm to the radially extending portions of the band. Inasmuch as the band is relatively thin it will 50 not offer resistance to flexing action so as to merely cause the band to contact at but a few points upon the periphery of the cam ring, but will have a tendency to deliver the forces along the band so that pressure is applied uniformly and evenly throughout the 55 60 surfaces of contact between the band and the cam ring.

Having thus described my invention what I claim is:

1. In a timing device for magnetos com-

prising an interrupter housing having a cam ring the combination of an annular band parted along a radius thereof and having radially extending portions at the parting thereof, a timing arm having an end thereof between said portions and means for securing said portions to said end of said arm and for tightening said band about said ring. 65 70

2. In a timing device for magnetos comprising an interrupter housing having a cam ring, the combination of an annular band parted along a radius thereof and having radially extending portions at the parting thereof, a timing arm having an end thereof between said portions, said portions having reinforcing return-bent portions, and means 75 80 for securing said reinforced portions to said end of said arm and for tightening said band about said ring.

3. In a timing device for magnetos comprising an interrupter housing having a cam ring, the combination of an annular band parted along a radius thereof and having radially extending portions at the parting thereof, a timing arm having a tongue between said portions and means for securing 85 90 said portions to said tongue and for tightening said band about said ring.

4. In a timing device for magnetos comprising an interrupter housing having a cam ring, the combination of an annular band parted along a radius thereof and having radially extending portions at the parting thereof, a timing arm having a tongue located between said portions, said portions having reinforcing return-bent portions, and 95 100 means for securing said reinforced portions to said tongue and for tightening said band about said ring.

5. In a timing device for magnetos comprising an interrupter housing having a cam ring, the combination of an annular band parted along a radius thereof and having radially extending return-bent portions at the parting thereof, a timing arm having a tongue between said portions, and common 105 110 means for moving said portions toward each other for tightening said band about said ring and for securing said portions to said tongue and in tightened position.

6. In a timing device for magnetos comprising an interrupter housing having a cam ring, the combination of an annular band parted along a radius thereof and having radially extending portions adjacent the parting thereof, a slotted timing arm having 115 120 flexible tongues adjacent the slit thereof and located between said portions and means for securing said ends to said tongues and for flexing said tongues for tightening said band about said ring. 125

In testimony whereof I affix my signature.

WOLFGANG E. SCHWARZMANN.
